UNITED STATES PATENT OFFICE

ALBERT H. LAKE, OF ROCHESTER, NEW YORK, ASSIGNOR TO THE SYMINGTON COMPANY, OF NEW YORK, N. Y., A CORPORATION OF MARYLAND

JOURNAL BOX

Application filed January 5, 1929. Serial No. 330,516.

This invention relates to journal boxes and more particularly to a lid pivotally mounted thereon and provided with resilient means for holding said lid in open or closed position.

The principal object of my invention, generally considered, is to provide a spring pressed lid for journal boxes, said lid being provided with an outstanding and upwardly extending hood forming hinging ears for the lid and housing a spring pressed lever which urges the lid tightly over the outer opening in the box, the construction providing for a large increase in pressure over that of previous designs.

Another object of my invention is to provide a journal box lid construction involving a cover portion with an integral outstanding hood providing hinging ears for pivotally mounting the lid to an associated box, said hood serving to house an associated lever and resilient means, preferably in the form of a pair of coil springs, acting between said lever and hood to hold the lid in open or closed position, the lower end of said lever being pivoted preferably adjacent the central portion of the lid, said central portion beneath said lever being inwardly embossed to facilitate assembly of the lever and spring with respect thereto.

A further object of my invention is to provide a journal box lid formed with an outstanding integral hood providing ears for hinging said lid with respect to an associated box and more particularly the hinge lug thereon, the central portion of said lid being provided with outstanding ears between which is normally disposed the lower end of a lever which is pivotally connected thereto, said lever being widened adjacent an intermediate portion thereof for receiving a pair of coil springs disposed between said lever and hood for actuating said lever and providing an increase in the pressure applied to said lid for holding it in engagement over the outer opening of an associated box.

Other objects and advantages of the invention relating to the particular arrangement and construction of the various parts

will become apparent as the description proceeds.

Referring to the drawing illustrating my invention, the scope whereof is defined by the appended claims.

Figure 1 is an elevational view of the outer face of one embodiment of my journal box lid, a portion of the hood and associated spring means being broken away to more clearly illustrate the construction of the lever.

Figure 2 is a transverse sectional view on the line 2—2 of Figure 1 looking in the direction of the arrows.

Figure 3 is a fragmentary transverse sectional view on the line 3—3 of Figure 1 looking in the direction of the arrows.

Figure 4 is a fragmentary side elevational view of the upper end of the hood and particularly the hinging loops thereof showing the split end of the associated pivot pin.

Referring to the drawing in detail, like parts being designated by like reference characters, there is shown a portion of a journal box 1 formed with the usual outer opening 2 normally closed by the lid 3. As is usual, the upper wall or roof of the box is formed with an upstanding and outwardly extending hinge lug 4 provided at its central portion with angularly disposed faces 5 and 6 adapted for respective engagement by a lid actuating lever 7 for holding the lid 3 in closed or open position. The lug 4 is provided with an aperture 8 receiving a pivot pin 9 serving to pivotally mount the lid 3 with respect to the box 1.

In the present embodiment, my lid 3 comprises a cover portion 10, the peripheral edge of which engages the peripheral edge of the journal box opening 2 to completely close the same. Outwardly and upwardly extending from the cover portion 10 and rigid or integral therewith is the hood or housing portion 11 which is extended, not only to provide a cover over the hinge lug 4, but also to provide hinging ears 12 formed with apertures 13 normally registering with the aperture 8 in the hinge lug for receiving the pivot pin 9. Disposed between the hood 11 and the cover 10 is the actuating lever 7 which

is resiliently urged against the hinge lug 4 by resilient or spring means 14, the outer ends of which engage the inner surface of the hood 11 and the inner ends of which engage the outer surface of the lever 7. The lower end of the lever 7 is preferably pivoted between outstanding lugs 15 on the outer face of the cover portion 10, as by means of a rivet or other pivoting means 16 extending through the lower end of the lever 7 or hinging ears 17 thereon.

In order to avoid the entrance of water and other foreign material into the box, the upper and side edges of the lid 3 are preferably formed with depending peripheral flanges 18, omitted only at the lug 4. The inner surface of the cover member 10 is preferably formed with an oil drip flange 19 for obviating loss of oil from the box. Between the hinge lugs 15 on the lid, a depression or inner embossment 20 is provided which increases in width above the lugs 15, as indicated at 21, for receiving the lever 7 during assembly of the spring and lever with respect to the cover and hood, the depth of the depression preferably decreasing to the upper edge of the cover 10. For rigidifying the cover, outstanding ribs or beading 22 are preferably provided on the outer face thereof.

The lever 7 preferably comprises a web 23 and an outstanding flange 24 disposed along the longitudinal center line thereof, said flange preferably increasing in depth to a maximum adjacent the center thereof or the center of the associated coil springs 14. The flange or web 24, as will be seen, acts as the main rigidifier for the lever 7. The side edges of the lever 7 are preferably formed with additional outstanding flanges or webs 25, said flanges at their intermediate portions curving outwardly around the widened portion of the web 23 and connected to the flange 24 by transverse webs 26 leaving spring seating pockets 27 therebetween. It will be seen that this construction provides a relatively large spring seating area enabling the use of a pair of coil springs 14, the inner ends of which fit in the pockets 27 and the outer ends of which engage a flat spring seating portion 28 on the hood bounded by shoulders 29 for holding the springs in place.

A desirable method of assembly of the lever and springs with respect to the hooded lid is as follows. The springs 14 are fitted in the spring pockets 27 in the lever 7 and said lever and springs placed in the depression 20 in the face of the lid or cover 10 and moved upwardly and outwardly until the outer ends of the springs 14 engage the portion 28 of the hood. The rivet or other pivoting means 16 is then applied and the lever is thereby pivotally mounted with respect to the lid or cover portion 10 thereof. Of course, when

the lid is disconnected from the box, the lever 7 will be urged into engagement with the upper edge of the cover portion 10 and force will have to be exerted to place the hinge lugs 12 on the hood 11 in position on opposite sides of the hinge lug 4 to permit insertion of the pivotal means or split pin 9. After assembly, the parts will take the position illustrated in Figures 1 and 2 when the lid is closed, and when in open position, the upper end of the lever 7 will engage the upper face 6 of the hinge lug 4 rather than the outer face 5 thereof.

From the foregoing description taken in connection with the accompanying drawing, it will be seen that I have devised a novel form of lid with an integral hood providing hinging ears, said hood serving for housing the upper end of an actuating lever and spring means therefor, the lower end of said lever being preferably pivoted adjacent the center of the lid. On account of the widening of the intermediate portion of the lever, I am able to use a pair rather than a single coil spring, thereby providing for a large increase in the pressure with which the lid is urged against the box. Although I have illustrated a preferred embodiment of my invention, it will be obvious that the disclosure should not be considered as limiting, for modifications may be made therein within the spirit and scope of the appended claims.

Having now described my invention, I claim:

1. In combination, a journal box having a hinge lug, a lid including a cover, a hood and a lever, said hood being rigid and said lever pivoted with respect to the cover, an intermediate portion of said lever being widened and formed with outstanding rigidifying web portions and a pair of coil springs seated on said widened portion and held in place by said outstanding portions, the outer ends of said springs being seated on the inner face of the hood for urging said lever inwardly to hold the lid firmly over the outer opening of the box and the upper end of the lever against the hinge lug, and means pivotally connecting said lid to said box.

2. A journal box lid including a cover with an integral hood portion extending outwardly and upwardly therefrom and opening downwardly, a lever disposed between said hood portion and cover, said cover being provided with lugs normally disposed on either side of said lever, intersecting the lower end of said lever and lugs for pivoting said lever to said cover, and spring means disposed between said hood, and an intermediate portion of said lever to hold said cover tightly over the outer opening in an associated journal box.

3. A journal box lid including a cover por-

tion, a hood and a lever, said hood being rigid and said lever pivoted with respect to the cover portion, an intermediate portion of said lever being widened and formed with an outstanding rigidifying web portion, and a pair of coil springs seated on said widened portion on opposite sides of said web portion, the outer ends of said springs being seated on the inner face of the hood for urging said lever inwardly toward the cover portion of the lid.

4. A journal box lid including a cover, a hood and a lever, said hood being rigid and said lever pivoted with respect to said cover, and spring means disposed between said hood and lever to force said lever toward said cover, the outer face of said cover having an inwardly embossed portion and outstanding lugs on opposite sides of said embossed portion, said lugs receiving the means pivoting the lever to the cover and said embossed portion being adapted to receive the lever to facilitate assembly thereof with respect to the hood and cover.

25 5. In combination, a journal box having an outer opening and a hinge lug, a lid including a cover and a lever, means for pivoting said lever with respect to said cover, bearing means on opposite sides of said lever receiving said pivoting means, said lever comprising a web with flanges at the sides thereof, a spring seated on the web of said lever, said web at the spring-engaging portion being widened as compared with that portion 30 of the lever between said bearing means, said flanges extending from said pivoting means toward said spring-receiving portion for rigidifying said lever and holding said spring in place, the end of said spring opposite to 35 that engaging said lever being seated on an integral portion of said cover for urging one end of said lever toward the hinge lug to hold the lid open or closed over the outer opening of the box, and means pivotally connecting 40 45 said lid to said box.

In testimony whereof I affix my signature.
ALBERT H. LAKE.
